MUSICAL TOY OR SIMILAR ARTICLE

William McLeod, Deerfield, and Jarvis W. Rockwell,
Chicago, Ill., assignors to Playskool Manufacturing
Company, Chicago, Ill., a corporation of Illinois

Filed Jan. 20, 1964, Ser. No. 78,294

Term of patent 14 years

(Cl. D34—15)

FIG. 3 is a side elevational view thereof.

The rear side is plain and unornamented.

We claim:

The ornamental design for a musical toy or similar article, substantially as shown and described.
